DOOR CLOSING AND CHECKING MECHANISM.

1,077,234.

Specification of Letters Patent.

Patented Oct. 28, 1913.

Application filed December 23, 1912. Serial No. 738,355.

To all whom it may concern:

Be it known that I, PERCY ALLIOTT SMITHURST, a subject of the King of Great Britain, residing at London, England, have 5 invented new and useful Improvements in Door Closing and Checking Mechanism, of which the following is a specification.

This invention relates to improvements in that class of door-closing mechanism where- 10 in a barrel contains a helical spring which is compressed as the door opens, either by the movement of a piston in the barrel or of the barrel on the piston, the said barrel and piston forming the air-check device, 15 the parts coacting so that the energized spring effects the closing of the door which closing is checked or retarded as the door approaches its closed position in order to prevent slamming.

20 By the improvements hereinafter described it will be observed that the compression of the spring is effected by a lever or bar interposed between a fixed abutment and a sliding plunger within the barrel, 25 whereby an increased leverage is obtained in the closing effect when the spring becomes less powerful toward the end of the closing operation, and the air-check plunger is operated separately by independent means.

30 In order that my said invention may be fully understood, I will proceed to describe the same with the aid of the accompanying sheet of drawings, in which—

Figure 1 is an elevation of a door-closing and checking mechanism constructed in accordance with my invention; Fig. 2 a plan view of same; Fig. 3 is a plan view similar to that shown in Fig. 2 but partly in horizontal section; and Fig. 4 a similar 40 plan view showing a modification in the construction of the air-check plunger and the application of an automatically actuated valve for destroying the retarding effect of the air-check as the door approaches the 45 closed position.

According to my invention I attach a bracket *a* to the door frame *b*, and to this bracket *a* I pivot, at *c*, a tubular closing lever *d*, which is connected to the door *e* by 50 means of a slide-guide *f* in which the end of the said tubular lever *d* is adapted to slide to a limited extent. On the bracket *a* is a pivot *g* on which is mounted, one end of a short bar *h*, the other end of which enters 55 the adjacent open rear end of the tubular lever *d* and engages with a plug *i* free to

slide in the said lever. Against the in- 60 nend of this plug *i* presses one end of an energized helical spring *j* compressed between the said plug *i* and a fixed abutment *k* within the tubular lever *d*. The bar *h* is preferably held in position by the pres- 65 sure of the energized spring *j*, that is to say its outer end may be so shaped, as shown in Fig. 3, as to bear against its pivot *g* on the bracket *a*, and its inner end may be so shaped as to rock in a curved recess in the outer end of the plug *i*, so that the said bar *h* is free to fall or be lifted away on the re- 70 moval from it of the pressure of the ener- gized spring *j*. At a suitable point on the bracket *a*, as at *m* for example, is also pivot- 75 ally mounted a bar *n* which extends exte- riorly of the tubular lever *d* to the farther end thereof, where it is pivotally connected to the outer end of a plunger *p* which slides more or less airtight within that portion of the tubular lever *d* which is on the opposite side of the fixed abutment *k* to that against which the spring *j* bears as before explained. 80 This plunger *p* is preferably fitted with a cup-leather *q*, and acts as an air-check, a small hole governed by a regulating screw, *r*, or any suitable arrangement of adjust- 85 able escape valve, being provided to allow of the gradual escape of air from the space between the inner end of the plunger *p* and the fixed abutment *k*. The points of pivotal attachment of the tubular lever *d* and the bar *h* respectively to the bracket *a* are 90 preferably so disposed that when the door is in the open position those two points are both in the line of force of the energized spring *j*, so that the spring has then no closing effect upon the door, and the latter 95 can be left in the open position when de- sired.

It will now be understood that the act of opening the door *e* will cause the tubular lever *d* to turn on its pivot *c* on the fixed 100 bracket *a*, and the energized or partly com- pressed spring *j* to be further compressed, as the bar *h* forces the plug *i* farther into the tubular lever *d*, and the external bar *n* will also cause the air-check plunger *p* to make a 105 stroke outward. Upon the door being re- leased the compressed spring *j* acting upon the abutment *g* on the bracket *a* through the plug *i* and bar *h* will, by acting upon the abutment *k*, force the tubular lever *d*, and 110 with it the door, into the closed position, as shown in the drawings, but the latter part of

the closing movement will be checked or retarded by the action of the air imprisoned between the plunger p and the abutment k , and the energy of the spring j will only be effective according as the plunger p is allowed to return slowly into its normal position by the gradual escape of the compressed air through the regulated escape hole or valve.

10 Referring now to Fig. 4. In order to allow the free entrance of air between the end of the air-check plunger p and the central abutment k in the pivoted tubular lever d during the outward stroke of such plunger, 15 instead of attaching the cup-leather q directly to the end of the plunger as described and shown in Fig. 3, I attach it to a loose end s which is carried by a pin t extending centrally from the end of the 20 plunger p . A washer u is interposed between the end of the plunger p and the loose end s , which latter is free to move on the central pin t for a short distance longitudinally of the axis of the plunger p . Air passages v are formed between the forward and 25 backward ends of the loose end s , which passages v are closed by the beforementioned washer u whenever the loose end s is pressed toward the plunger, that is to say at the forward stroke thereof; but when the 30 passages v are not so closed, that is to say at the backward stroke of the plunger, the air from the outer atmosphere is free to pass into the space between the loose end s and the 35 plunger p by suitable passages w formed in the end walls of the hollow plunger p , and thence into the space between the cup-leather q and the beforementioned central abutment k by the said passages v in the loose end s .

40 It will be understood that when the plunger p is withdrawn from the tubular lever d by the opening of the door e , the first pull on the plunger p will cause it to move away from the loose end s and uncover 45 the air passages v . Air will then freely pass from the outer atmosphere through the passages w in the plunger p , into the space between the loose end s and the end of the plunger p , and through the uncovered passages v in the loose end s into the gradually 50 increasing space between the cup leather q and the central abutment k in the tubular lever d . But on the reverse movement of the plunger p while the door is closing, the 55 first inward movement will press the plunger p , washer u , and loose end s all close together thereby closing the air passages v in the loose end s and insure that the air contained in the tubular lever d shall 60 pass through the opening governed by the ordinary regulating screw r , or otherwise.

In some cases it is desirable that the retarding effect of the air-check should more or less suddenly cease as the door ap-

proaches the closed position, (as for example when the latch of the door is sluggish in action), and the full effect of the spring j be exerted for the final closing of the door e . For this purpose I provide an outwardly closing spring valve x suitably mounted in the central abutment k of the tubular lever d with its stem y projecting from the exterior of the lever d in such a position that it comes within the path of a cam z mounted upon the external bar n which connects the outer end of the air-check plunger p to the bracket a fixed to the door frame b , by which inclined cam surface z the valve x is caused to open against the resistance of its spring o , and the compressed air contained between the acting end of the plunger p and the central abutment k of the tubular lever d is thereby allowed to escape freely, and the door-closing spring j , being no longer checked, closes the door e suddenly. The cam z is preferably mounted upon the bar n in such a manner that its position thereupon may be adjustably regulated according to requirements.

Claims:

1. A door-closing and checking mechanism which consists of a tubular lever pivoted to a fixed bracket, an energized spring contained within said tubular lever, means for compressing said spring as the door is opened, an air-check plunger device in said tubular lever, and means for actuating said plunger separate from and independent of those for compressing said spring, substantially as described.

2. A door closing and checking mechanism which consists of a tubular lever pivoted to a fixed bracket, an energized spring contained within said lever, means for compressing said spring which consists of a fixed abutment on said bracket, a plug within said tubular lever and a bar engaging said abutment and extending within said tubular lever and engaging said plug, an air check plunger device in said tubular lever and means for actuating said plunger separate from and independent of those for compressing said spring, substantially as described.

3. A door closing and checking mechanism which consists of a tubular lever pivoted to a bracket, an energized spring contained within said tubular lever, a fixed abutment on said bracket, a plug within said tubular lever and operatively engaging said spring, a bar engaging said abutment and said plug, an air check plunger contained within said tubular lever and furnished with a loose end, said loose end having air passages extending therethrough, a washer interposed between said loose end and the end of said plunger, the inner end of said plunger having air passages ex-

90

100

tending therethrough and means for operating said air check plunger, substantially as described.

4. A door closing and checking mechanism which consists of a tubular lever pivoted to a bracket, an energized spring contained within said tubular lever, a fixed abutment on said bracket, a plug within said tubular lever and operatively engaging said spring, a bar engaging said abutment and said plug, an air check plunger contained within said tubular lever, a bar connecting said air check plunger with said bracket, an abutment within said lever between said spring and the inner end of said

plunger and provided with an opening communicating with the atmosphere and with the space between said abutment and said plunger, a valve controlling said opening, means normally tending to hold said valve closed and means for moving said valve into its open position when the door approaches its closed position.

In testimony whereof I have signed my name to this specification in the presence of 25 two subscribing witnesses.
